UNITED STATES PATENT OFFICE

2,200,590

HAIR CURLER

Benjamin Black, Brooklyn, N. Y.

Application November 17, 1939, Serial No. 304,887

18 Claims. (Cl. 132—33)

This invention relates to devices such as hair curlers.

One object of the invention is to provide a device having improved means for clamping and 5 curling a hair curl after formation thereof by the device.

Another object of the invention is the provision of a jaw-type hair curler having removably mounted means for the clamping and withdrawal 10 of a curl of hair, constructed so as to maintain the curl in tensioned and accurately formed condition.

Another object of the invention is to provide a device having such improved removably mounted 15 means in the form of a sheet material structure comprising a relatively rotatable sleeve and a preferably integral spring clamp, with one jaw slotted to avoid obstruction of the spring catch with the jaws in moving the spring to clamping 20 position while the sleeve is mounted on the slotted jaw of the device.

Another object of the invention is to furnish a one piece hair curl clamp comprising a tube and strip spring integrally connected at one end 25 of the tube and having a releasable integral catch at its other end for engaging in the corresponding end of the tube.

Another object of the invention is to provide a hair curler device having pivotal jaws one of 30 which is slotted and carries a removable rotary tube having a spring clamp connected to the end of the tube remote from the pivot of the jaws, the slot permitting a catch on the free end of the spring clamp to easily engage in said tube 35 when the catch is in the plane of the slot to permit removal of the tube with the catch in engaged position, and improved means coacting with the parts mentioned for causing alinement of the catch with said slot to facilitate the engagement of the catch with the tube.

A further object of the invention is to provide a device of the type mentioned having relatively few and simple parts and which is inexpensive to manufacture and assemble, compact and convenient, durable, and efficient to a high degree 45 in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed 50 drawing, wherein like parts are designated by the

same reference characters throughout the several views.

In the drawing:

Figure 1 is a top plan view in closed position showing a hair curler embodying the invention.

Fig. 2 is a fragmentary sectional view on line 2—2 of Fig. 1.

Figs. 3, 4, and 5 are sectional views taken on the respective lines 3—3, 4—4, and 5—5 of Fig. 1.

Fig. 6 is a side view of the device in fully open position.

Fig. 7 is a side view of the removed curl clamp in closed position.

Fig. 8 is a top plan view of the curler with the clamp part removed.

Fig. 9 is a view in open position of a modified device.

Fig. 10 is a section on line 10—10 of Fig. 9.

Fig. 11 is a longitudinal sectional fragmentary view showing another modification.

Fig. 12 is a fragmentary view of the same showing the clamp swiveled to a different position.

Fig. 13 is a sectional view taken on the line 3—3 of Fig. 12.

Fig. 14 is a sectional view taken on line 14—14 of Fig. 11.

Fig. 15 is a perspective view of a modified clamping device.

Fig. 16 is a sectional view showing the coordination thereof with any jaw device herein shown.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 15 denotes a device embodying the invention. The same includes a rotary curler part which may include a plurality of jaws 16, 17, pivotally interconnected at 18 and providing finger piece portions 19, 20 between which is seated a U-shaped strip spring 50 21 expandible for moving the jaws toward each other. Upon the jaw 16 there may be rotatably mounted a curler device so that it can be held in the hand while the jaw structure 16, 17 is rotated with the curler device acting as a bearing. 55

As thus far described, the structure is conventional.

According to the invention, the jaw 16 is formed as a grooved element, and it may consist of a tube having a slot 22 extending from the free end of the jaw to a point 23 at which the tube is circular in cross section, for reenforcement, being cut away in part at its other end to form the finger piece 20. The other jaw 17 is of generally arc shape in cross section and is formed with opposite ears for the pivot pin 18 which extends through the tubular part of the jaw 16.

The companion part 24 of the hair curler includes a tube 25 having a strip element or spring 26 connected at one end 27 to the tube and having at its other end a catch 28 adapted to releasably snap into the adjacent end of the tube. The part 24 may be made as a one piece sheet material structure, with the material folded to provide a tube which is thus longitudinally split as at 29 at the side thereof facing the spring 26, and the latter being integrally struck out of said sheet material for the integral connection at 27. The tube 25 may have perforations (not shown) to facilitate drying of the hair.

The jaw 16 is inserted into the tube 25 which acts as a bearing for rotation of the jaws 16, 17, with the clamp 26 in open position. Upon pressing the clamp element 26 downwardly, the catch 28 passes through the groove or slot 22 to snap into engagement with the adjacent edge of the tube 25. Now the jaw 16 may be withdrawn with the catch 28 in closed position riding in the slot 22 until the jaw 16 has been completely removed.

To assure easy alinement of the catch 28 with the slot 22, the tube 25 may be provided with a tit 30 projecting releasably into a corresponding shallow recessed portion 31 of the jaw 16 as shown in Fig. 6. When the operator feels the engagement or hears the click, she knows that the desired alinement has occurred. Any forcible turning will release the projection 30.

In Figs. 9 and 10 is shown a modification 32 which is generally like the device 15, except that 45 the slotted jaw 16a externally engages around the tube 25a so that the latter acts as a shaft and the jaw 16a as a bearing. The operation of the spring and catch elements 26, 28 is the same as before. This device 32 is not as desirable as the device 15 because the hair is curled around the jaw 16a instead of directly on the tube 25a. Hence when the curl is withdrawn onto the tube 25a, it loses 50 desirable tension because the tube 25a is substantially smaller in diameter than the jaw 16a.

In Figs. 11 to 14 is shown a modification 33, which permits alinement of the catch 28 with the slot 22 at all points of turning of the jaws so that the clamping spring 26 can be applied as closely to the scalp as possible. Accordingly, the detent 55 such as 30, 31 of Fig. 6 may be omitted.

In principle, one jaw of the device 33 is journaled on the other jaw which is inserted into the tube of the clamp 24, and a projection on the tube 25 engages in the slot 22 to prevent rotation 60 of the slotted jaw. For example, the tube 25b may have free end portions at 34 bent into the slot 22 for guiding engagement therein, as indicated in Fig. 13, but this will not prevent the engagement by the catch 28 as hereinbefore described.

The slotted jaw 16b may have a tubular part, shown in Fig. 14, which is annularly recessed at 35 to form a bearing. Engaged in this bearing is a ring or collar 36 which is thus held against 70 removal. Fixed to this collar is a finger piece 37

which thus extends beyond the adjacent end of the jaw 16b. Pivotedly mounted on the collar 36 at 38 is the jaw 17b affording a finger piece 39. Thus while the jaw 17b is rotatable about the jaw 16b, the fingers 37, 39 are always in operative 5 alinement and may be spring pressed apart by the U-spring 21. Since the projection 34 is at the mouth of the tube 25b the sleeve jaw 16b is instantly easily alined for operation of its slot 22, irrespective of the angular position of the 10 jaw 17b about the axis of rotation.

In operation, all the hair curlers shown are alike, especially those shown in Figs. 1 and 12. A strand of hair is engaged under the external jaw such as 17, 17a, or 17b, and the tube such as 25, 15 25a or 25b held stationary while the jaw structure is revolved to form the curl. Then the spring element 26 is locked to retain the curl and the other jaw such as 16, 16a or 16b removed, with the catch 28 riding in its adjacent slot and stripping off the curl of hair for tight, reliable retention thereof.

In Figs. 15 and 16 is shown a modified clamping device 40 comprising a pair of members 41, 42 integrally interconnected at one end as by a 25 resilient curved portion 43, and having at the other end interengaging means. The latter include a catch portion or nose piece 44 on the movable arm 42 for releasable snap engagement under the end of the arm 41, which may be concaved at 45 as shown. Thus the device 40 may be very cheaply struck out of sheet material, with the arm 41 having sufficient width to adequately carry a curl of hair wrapped therearound. This arm 41 may be regarded as longitudinally ribbed 30 or otherwise reenforced.

According to Fig. 16, the arm 41 is coordinated with a jaw member 16 or 16a or 16b so as to properly seat the latter for rotation, as, for instance, with the arm 41 having parallel edges diamet- 40 rically engaging the interior of the jaw member. Thus the arm is disposed to afford space for engagement of the nose piece 44 under the edge 45 by merely pressing down on the arm 42. In operation, the clamping device 40 functions 45 throughout like the device 24.

I claim:

1. A hair curler comprising a pair of pivotally interconnected jaw members, and a clamping device including a bearing member with which 50 one of the jaw members is removably rotatably engaged, and a spring clamping element connected to the bearing member at an end thereof remote from the pivotal axis of the jaw members and being releasably locked with the end of 55 the bearing member nearest to said pivotal axis, the removable jaw member having a longitudinal opening extending substantially throughout the length thereof to permit locking engagement of the spring element and to permit removal of 60 the removable jaw member with the spring element maintained in locked position, the other jaw member serving as a starting clamp for a lock of hair, and the said jaws being rotatable as a unit when the clamping element is in open position in course of forming the lock of hair into 65 a curl.

2. A hair curler including a clamping device for holding a curl, comprising a first member and a second member, a first jaw member and 70 a second jaw member, said jaw members being pivotally interconnected, the first jaw member being removably engaged with the first member of the clamping device, the second member of the clamping device being in normally open po- 75

- sition and being connected to the first member thereof at a point remote from the pivotal axis and having means for releasable locking engagement with the first member of the clamping device adjacent to said pivotal axis, the second jaw member being mounted so as to be revoluble about the first member of the clamping device when the second member thereof is in said open position, the second jaw member serving to clamp the end of a lock of hair against one of said first members to wind said hair into a curl upon revolution of the second jaw member, the first jaw member having a longitudinal opening open at its free end for passage of the said means of the second member of the clamping device into locking position for the curl of hair and to permit removal of the clamping device with said means maintained in locking position, said longitudinal opening extending substantially throughout the length of the first jaw member. 5
10. A hair curler according to claim 2, including means for causing alinement of the slot and said means. 10
11. A hair curler according to claim 2, wherein said members of the clamping device constitute a one piece structure. 15
12. A hair curler according to claim 2, wherein the first member of the clamping device consists of a tube formed of sheet metal with the second member thereof being integral with said tube and the said means consisting of a resilient tongue engageable in said tube. 20
13. A hair curler according to claim 2, wherein the first jaw member is journaled within the first member of the clamping device, means being provided for preventing rotation between the said first members to cause the said locking means to be maintained in alinement with the said longitudinal opening, and means being furnished rotatably mounted on the first jaw member for pivotally supporting the second jaw member. 25
14. A hair curler according to claim 2, wherein the first jaw member is journaled within the first member of the clamping device, means being provided for preventing rotation between the said first members to cause the said locking means to be maintained in alinement with the said longitudinal opening, said last mentioned means being located at that end of the first member of the clamping device nearest to said pivotal axis and projecting into said longitudinal opening, and means for rotatably mounting the second jaw member on the first jaw member to permit the said pivotal movement of the second jaw member in different positions. 30
15. A hair curler according to claim 1, wherein said bearing member consists of a tube in which the removable jaw member is journaled. 35
16. A hair curler according to claim 1, wherein in said bearing member consists of a tube in which the removable jaw member is journaled, said spring clamping element being permanently connected to said tube. 40
17. A hair curler according to claim 2, wherein the first and second members of the clamping device are integrally interconnected and are of relatively plane construction. 45
18. A hair curler according to claim 2, wherein in the first and second members of the clamping device are integrally interconnected and are of relatively plane construction, the first member being of sufficient width to seat along a diametral plane within the first jaw member, and the latter being a tube, whereby the releasable locking means is afforded space for engaging under a free end of said first member within the tube, at one side of said diameter. 55
19. A hair curler according to claim 2, wherein means is provided for preventing rotation between the said first members to thus maintain the said locking means in alinement with said longitudinal opening, and means rotatably mounted on the first jaw member pivotally supports the second jaw member. 60
20. A hair curler according to claim 2, wherein means is provided for preventing rotation between the said first members to thus maintain the said locking means in alinement with said
